UNITED STATES PATENT OFFICE.

HENRY A. CURRIER, OF ALMONT, MICHIGAN.

LAND-ROLLER.

SPECIFICATION forming part of Letters Patent No. 313,813, dated March 10, 1885.

Application filed June 23, 1884. (No model.)

To all whom it may concern:

Be it known that I, HENRY A. CURRIER, of 5
Almont, in the county of Lapeer and State of
Michigan, have invented certain new and use-
ful Improvements in Rollers; and I do hereby
declare the following to be a full, clear, and
exact description of the invention, such as will
enable others skilled in the art to which it
pertains to make and use it, reference being
10 had to the accompanying drawings, which
form part of this specification.

My invention relates to an improvement in
rollers; and it consists in the combination of
15 a rod which passes through all of the sections,
the end pieces having suitable gudgeons
formed thereon, the hubs, and the castings
which are secured to the hubs, as will be more
fully described hereinafter.

The object of my invention is to produce a
20 land-roller in which the hubs are made in sepa-
rate and distinct parts, so that they can be re-
placed when worn out, and in which the va-
rious parts can be easily lubricated.

Figure 1 is a vertical longitudinal section of
25 a roller embodying my invention. Figs. 2, 3,
and 4 are detail views.

A represents a rod by means of which the
various sections are united together, and which
has a head, B, formed upon one end, and a
30 screw-thread upon the other to receive the
clamping-nut C. There may be either one,
two, or more sections, D, to the roller, as may
be preferred. At each end of each section of
the roller is formed a circular metallic frame
35 or casting, E. At the outer inner edges of
these castings E are formed the flanges G, in
between which the ends of the boards or rods
which form the roller proper are clamped, the
boards and castings being bound together by
40 tie-rods F. Through the center of each of
these castings E is formed an opening large
enough for a portion of the hub H to pass
through. These castings are bolted to the
hubs H by means of the flanges I, formed on
45 the hubs, and the bolts J. These hubs H are
made tapering upon their inner sides, and
have their inner ends contracted so as to fit
snugly around the rod A. Where the two sec-
tions D are fastened together, as here shown,
50 the ends of the frame or support L are pro-
vided with the bearings or gudgeons N at their

lower ends, which gudgeons project into the
hubs, as shown. Upon the inner sides of the
parts L are formed the flanges O, which catch
over the outer edge of the gudgeon N, for the
purpose of forming a tight joint or dust-band
55 to keep the dust and dirt from working into
the bearings. In each one of these gudgeons
or bearings N is made a suitable oil-chamber,
a, in which oil can be poured, and which will
gradually work out of the bearing into the
60 hubs, so as to lubricate the moving parts. The
rods A and the parts L have no movement,
while the hubs H revolve around the parts N.
Through the upper ends of the parts L are
65 made suitable slots, P, so that when the parts
are secured together the frame can be adjusted
so as not to cause any binding between the
moving parts. Where two sections, D, are
70 secured together, as here shown, a central frame
or casting, Q, is used, which projects
upward between the ends of the two sections,
and which has the tongue or pole secured upon
its top, as shown in Fig. 4. Upon the top of
75 this tongue or pole will be secured the driv-
er's seat. Through the lower part of the cast-
ing Q is made an opening for the rod A to
pass through, and to opposite sides of this
lower perforated part are clamped the two
80 central gudgeons or bearings, R, which are
shaped and constructed as shown in Fig. 2.
The outer ends of these gudgeons project into
the hubs H, and upon the gudgeons are formed
suitable flanges, which catch over the outer
85 ends of the hubs for the purpose of forming dust-
bands, as above described. These gudgeons
R are made hollow, as shown, so as to receive
oil, and this oil is fed into these gudgeons by
means of the pipe T, which projects down from
90 the frame in the rear of the seat into the cen-
tral iron between the gudgeons, and flowing
thence into the gudgeons. The oil is poured
through this pipe T until the chambers in the
gudgeons are filled, and from these chambers
95 the oil will gradually find its way into hubs,
so as to lubricate the different parts. The hubs
are all made detachable, as here shown, so that
when they become worn out, broken, or in-
jured they can be readily removed and re-
placed by others. By means of the construc-
100 tion here shown the bearings can be kept con-
stantly oiled.

I am aware that it is not new to journal a number of rollers or sections of rollers upon a single rod or shaft, and this I disclaim.

Having thus described my invention, I 5 claim—

1. In a land-roller, the combination of two or more sections, D, a rod which passes through all of the sections, the end frames, L, provided with the gudgeons or bearings, the hubs, and 10 the frames E, substantially as described.

2. In a land-roller, the combination of the rod A, the two sections D, each one of which is provided with the end frames, L, and gudgeons N, the castings E, and hubs H, with the 15 central casting, Q, and suitable gudgeons secured thereto, substantially as described.

3. In a land-roller composed of two or more sections, D, the combination of the frame Q, the two hollow gudgeons R, which are secured thereto, the hubs H, the frames E, and the 20 rod A, the gudgeons being adapted to be filled with oil through the pipe T, substantially as specified.

In testimony whereof I affix my signature in presence of two witnesses.

HENRY A. CURRIER.

Witnesses:

C. R. FERGUSON,
F. P. McHARDY.
